DESIGN FOR A CURTAIN

Julius Steinberg, New York, N. Y.

Application July 9, 1936, Serial No. 63,741

Term of patent 3½ years

To all whom it may concern:

Be it known that I, Julius Steinberg, a citizen of the United States of America, residing in Manhattan, county of New York, and State of New York, have invented a new, original, and ornamental Design for a Curtain, of which the following is a specification, reference being had to the accompanying drawing, forming part thereof, wherein,

Figure 1 is a plan view of a curtain showing my new design.

Figure 2 is a fragmentary portion of the body of the curtain drawn to the actual scale and embodying one complete motif of the design together with the open work texture of the blocks forming the body of the curtain surrounding the motifs.

I claim:

The ornamental design for a curtain, substantially as shown and described.

JULIUS STEINBERG.
